United States Patent Office

Des. 217,863
Patented June 23, 1970

217,863

CHAIR

Wayland B. Parker, South Boston, Va., assignor to Schlumberger Limited (Schlumberger N.V.), New York,
N.Y., a corporation of the Netherlands Antilles

Filed Apr. 9, 1969, Ser. No. 16,646

Term of patent 14 years

Int. Cl. D6—01

U.S. Cl. D15—1

FIG. 1 is front elevational view of a chair in accordance with my design;

FIG. 2 is a rear elevational view thereof;

FIG. 3 is a side elevational view thereof;

FIG. 4 is a top plan view; and

FIG. 5 is a bottom plan view thereof.

The side not shown is a mirror image of the side shown in FIG. 3.

I claim:

The ornamental design for a chair, substantially as shown and described.
